UNITED STATES PATENT OFFICE.

ERNEST J. CROCKETT, OF LOS ANGELES, CALIFORNIA, ASSIGNOR, BY MESNE ASSIGNMENTS, OF ONE-HALF TO A. M. YOUNG AND ONE-HALF TO G. JOHNSON RITTENHOUSE, BOTH OF LOS ANGELES, CALIFORNIA.

METHOD OF MAKING RECEPTACLES.

1,263,647.

Specification of Letters Patent. Patented Apr. 23, 1918.

Application filed March 30, 1915, Serial No. 18,002.

Renewed September 17, 1917. Serial No. 191,904.

To all whom it may concern:

Be it known that I, ERNEST J. CROCKETT, a citizen of the United States, residing at Los Angeles, in the county of Los Angeles and State of California, have invented a new and useful Method of Making Receptacles, of which the following is a specification.

An important object of this invention is the production of a receptacle by a method 10 that is inexpensive and that will effect great strength of the receptacle even though some of the material used in its manufacture may be in itself, previous to its incorporation in the product, incapable of withstanding great 15 strains.

Another object is to so wind and arrange strip material such as paper or other fibrous material as to produce receptacles of maximum strength and minimum liability to 20 leak.

Another object is to so arrange strip material in layers as to produce maximum smoothness of the inside and outside surfaces of the receptacles.

25 Another object is to so wind strip material as to make the winding operation continuous.

Other objects and advantages may appear from the subjoined detail description.

30 Figure 1 is a rear elevation of a machine for making barrels, kegs or the like in accordance with this newly invented method, supplied with strip material.

Fig. 2 is a side elevation from line indicated by $\alpha^2-\alpha^2$, Fig. 1 looking toward the right, portions being broken away for clearness of illustration.

Fig. 3 is a broken plan view of Figs. 1 and 2, showing the core wrapping.

40 Fig. 4 is a cross section of the core-body on line indicated by $\alpha^4-\alpha^4$, Fig. 5.

Fig. 5 is a longitudinal mid section of the core.

Fig. 6 is an enlarged detail of some of 45 the parts on line indicated by $\alpha^6-\alpha^6$, Fig. 2.

Fig. 7 is an end plan view of the completed receptacle.

Fig. 8 is an enlarged fragmentary section on line indicated by $\alpha^8-\alpha^8$, Fig. 7.

50 Generally stated, the method or process comprises winding strip material in helical turns to form layers, the helical turns in one of said layers diagonally crossing the helical turns in another of said layers, so

that the helical turns of alternate layers 55 progress aslant toward one end of the receptacle, and the helical turns of adjacent layers progress aslant toward opposite ends of the receptacle, and adjacent layers overlap one another. 60

Winding of the strips may be accomplished by hand, if so desired, but to facilitate production and to practically perform the winding process automatically, I have shown in the drawings a machine analogous 65 to the disclosure in my copending application for receptacle making machine, filed April 5, 1915, Serial No. 19,112, it being understood that I do not limit the method to its being carried out by the machine herein disclosed, as any suitable machine for performing the operations hereinafter disclosed will answer the purpose and spirit of this invention. 70

Spools 4, 5, 6 to hold cartridges or rolls 75 of strip material such as paper or other fibrous material are mounted on suitable spindles 7 carried by a standard 8 of a frame 9. The spools 4, 5, 6 are in staggered relation with one another and the strips 10-11 80 from the lower spools 4, 5 are threaded over a guide or roller 12 mounted on the standard and the strip 13 from the upper spool 6 is threaded under said roller. All of the strips 10, 11, 13 are threaded around a guide 85 roller 14 and over a roller 15 which is rotatably mounted on an adjusting arm 16 pivoted to the upper end of an oscillating feeder arm 17 and pivoted to a connecting rod 18 that in turn is pivoted to an operating lever 90 19 pivoted to said feeder arm, so that movement of the lever 19 will raise and lower the roller 15 in order to alternately bring the strips 10, 11, 13 out of and into engagement with a distributing roller 20 rotatably 95 mounted in a tank 21 designed to contain a suitable compound such as glue, silicate of soda and alum. Thus the compound is spread on the under surfaces of the strips 10, 11, 13 by the distributing roller 20, as 100 the strips pass over said roller.

The strips 10, 11, 13 are threaded from the distributing roller 20 over a guide roller 22 rotatably mounted on the feeder arm 17. The rollers 12, 14, 15, 22 may be provided with flanges 23 to prevent the edges of adjacent strips overlapping one another. 105

The feeder arm 17 is pivoted at its lower

end at 24 to the frame 9 and is pivoted intermediate its ends at 25 to one end of an actuating rod 26 which is provided at its opposite end with a pivot 27 engaging a slot 28 in the lower end of a lever 29.

The lever 29 is fulcrumed intermediately at 30 to the frame 9 and is provided at its upper end with a slot 31 engaged by a stud 32 which projects from a collar 33 reciprocably mounted on a cam shaft 34 having a cam track in the form of reversely directed helical grooves 35, 36, and end grooves 37 connecting the ends of the groove 35 to the ends of the groove 36, each of the grooves 37 being approximately one-half of a straight turn.

The grooves 35, 36, 37 accommodate a crescent shaped follower 38 having a stud 39 projecting into a seat 40 located in the collar 33, said seat extending up through a boss 41 that is externally threaded to receive a cap 42 into which is screw threaded a lubricating cup 43.

The cam shaft 34 rotates in bearings 44, 45 of the frame and is provided on its outer end with a sprocket wheel 46 engaging a sprocket chain 47 which is driven by a sprocket wheel 48 mounted on the outer end of a shaft 49 journaled at 50, 51 on the frame 9, said shaft being provided with fast and loose pulleys 52, 53 to receive a driving belt, not shown, which drives the shaft 49 when said belt engages the fast pulley 52 and which can be shifted by the usual means, not shown, from said fast pulley to the loose pulley 53 when it is not desired to operate the machine.

The shaft 49 operates a collapsible core of suitable construction and in the instance shown, said core comprises heads 54, 55 and an intermediate barrel shaped core-body formed of longitudinally curved segments 56, 57 which are pivoted at 58, 59 to arms 60, 61 respectively that are pivoted at 62 to hubs 63 fastened by keys 64 or the like to the shaft 49, said arms 61 being sectional and provided with knuckle joints 65.

The shaft 49 is provided with a conical centering end 66, and the head 54 is provided with a hub 67 fastened by a key 68 or the like to the shaft 49, and the head 55 is provided with a centering pin 69 fastened to said head by a key 70 or the like, said centering pin having a conical centering end 71 designed to be in alinement with the centering end 66 of the shaft when the head 55 is in place.

The centering pin 69 is provided with a conical centering socket 72 to receive the conical end of a pivot 73 which is mounted in one end of a swinging arm 74 that is pivoted at the other end at 75 to a bracket 76 of the frame 9, said swinging arm 74 being yieldingly held toward the head 55 to hold said head in place by a coil spring 77

fastened at its opposite ends to the swinging arm 74 and frame 9.

The head 54 is provided with a spring clip 78 beneath which the ends of the strips 10, 11, 13 may be caught as in Fig. 3.

The method is carried out on the machine above described as follows:

The tank 21 will be provided by the attendant with a suitable binding compound such as glue, silicate of soda and alum, and the spindles 7 will be supplied with spools of strip material such as paper or the like and the strips 10, 11, 13 will be threaded to engage the guide rollers 12, 14, 15 and 22. The lever 19 will be operated to raise the roller 15, thus to hold the strips 10, 11, 13 free from the distributing roller 20. A permanent head 79 of wood or other suitable material having centering sockets 80 will then be placed at the forward end of the core between the core-body and the head 55 as in Fig. 2.

Assuming at the start that the feed arm is in such position that the roller 22 is directly over the head 54, the free ends of the strips 10, 11, 13 will be fastened under the spring clip 78 and the machine will then be started into operation by turning the driving pulley 52 by a power driven belt, not shown, so as to turn the core in the direction of the large feathered arrow 81, Fig. 1, to wind the strips with abutting edges in helical turns progressing toward the head 55 to form an inner layer *a*. When the cam shaft has rotated sufficiently to swing the feed arm far enough so that the upper end of said arm is adjacent the head 55, the layer *a* is completed.

The cam shaft 34 causes the feed arm to swing from the head 54 along the core-body to the head 55 to wind the strips around the head 55, whereupon the lever 19 will be operated to lower the roller 15 to allow the strips 10, 11, 13 to contact with the distributing roller 20 and said cam shaft then reverses the movement of the feed arm so as to wind the strips in a reverse direction overlapping the turns in the first layer and diagonally crossing the turns of the first layer *a*, thus forming a second coated layer *b* bound by the glue to the first layer.

Thus the feed arm is caused to swing to and fro to wind the strip material to and fro around the form as the core revolves and the winding operation is continued until any desired number of layers have been wrapped on the core to form a tubular body, there being five layers *a*, *b*, *c*, *d*, *e* forming the tubular body, shown in Figs. 7 and 8.

When the desired number of layers have been formed, the operator will sever the unwound portions of the strips 10, 11, 13 from the wound portions thereof and he will then operate the arms 61 to bend the same at the knuckle joints 65 to cause the segments 57

- to be drawn radially inward toward the shaft 49. This may be done by the operator passing his arm into the interior of the core through one of the openings in the head 54, 5 see Fig. 1; or any suitable mechanism, not shown, may be connected to the arms 61 whereby to bend them. The operator will then grasp the tubular body and pull the same forward together with the head 79 10 away from the head 54, thus causing the arms 60, 61 to swing forward and the segments 56 to collapse inward alongside of the segments 57 so as to free the tubular body from the core.
- 15 The wound strips 10, 11, 13 will then be trimmed off by hand or otherwise to leave tongues 82 at both ends of the tubular body, the tongue at the headed end projecting sufficiently beyond the outer face of the head 79 20 to receive a channeled rim 83 as in Fig. 8. The operator will place the rim 83 over the tongue adjacent the head 79 and he will then drive nails 84 or the like through the rim and through the strips and into the edge 25 of the head 79, thus securely fastening said head in place and strengthening the end of the receptacle.

If it is desired to have heads at both ends of the receptacle, a second head will be 30 fastened in place at the other end of the receptacle in the same way as just described for the head 79, and if it is not desired to have a second head, a rim analogous to the rim 83 will be fastened in place 35 at said other end of the receptacle, the duplicate construction being obvious without it being necessary to more fully show and describe said construction.

It is noted that by winding the strip material in one direction in helical turns increasing in diameter from one end of the core to the median portion of the core and decreasing in diameter from said median portion to the opposite end of the core the 40 endwise crushing strength of the receptacle is maximized, for if the strips were wound to form a straight tube the walls would 45

crush under considerably less force than would be required to crush the receptacle having the bulge to its walls as provided 50 for by my method.

I claim:

1. The method of making receptacles, which method comprises holding a head against a core, winding strip material over 55 the core and around the head in one direction in helical turns increasing in diameter from one end of the core to the median portion of the core and decreasing in diameter from said median portion to the opposite end 60 of the core to form a layer, then winding said strip material in the opposite direction to form a second layer over the first layer, and then fastening the head to both of said 65 layers.

2. The method of making receptacles, which method comprises holding a head against a core, wrapping strip material spirally in superposed layers around the periphery of the core and head so as to extend beyond the outer face of the head to 70 form an annular tongue, separating the head and body from the core, and then fastening a grooved rim over the tongue and to the head to hold the superposed layers and head 75 together.

3. The method of making receptacles, which method comprises placing a head against a core, wrapping strip material 80 spirally to and fro in superposed layers and continuous from layer to layer and beyond the outer face of the head so as to form an annular tongue composed of layers of the material, inserting all of the layers of the tongue in a grooved rim, and then fastening 85 the rim to the head to hold said layers and head together.

In testimony whereof, I have hereunto set my hand at Los Angeles, California, this 24th day of March, 1915.

ERNEST J. CROCKETT.
